UNITED STATES PATENT OFFICE.

JOSIAH SCOTT SCARBOROUGH, OF NEW PHILADELPHIA, OHIO.

OILING DEVICE.

SPECIFICATION forming part of Letters Patent No. 606,303, dated June 28, 1898.

Application filed July 7, 1897. Serial No. 643,739. (No model.)

To all whom it may concern:

Be it known that I, JOSIAH SCOTT SCARBOROUGH, a citizen of the United States, residing at New Philadelphia, in the county of 5 Tuscarawas and State of Ohio, have invented certain new and useful Improvements in Oil-ing Devices; and I do hereby declare the following to be a full, clear, and exact description of the invention, such as will enable others 10 skilled in the art to which it appertains to make and use the same.

My invention relates to a novel form of oil-ing device for vehicles and general machine use; and the object is to provide a simple, 15 inexpensive, and convenient oiler of this class.

To this end the novelty consists in the construction, combination, and arrangement of the same, as will be hereinafter more fully described, and particularly pointed out in 20 the claims.

In the accompanying drawings the same reference characters indicate the same parts of the invention.

Figure 1 is a vertical section of a portable 25 oil-can embodying my invention. Fig. 2 is a modification of the same, showing the discharge-spout applied to a monkey-wrench. Fig. 3 is another modification showing the discharge-spout applied to a socket-wrench. 30 Fig. 4 is a horizontal section of the oil-can shown in Fig. 1. Fig. 5 is a detail view of the valve-sleeve.

1 represents the oil-can, provided with a vertical concentric tube 2 and a fixed internally-threaded collar 3.

4 represent four radial partitions which divide the can into four oil-compartments 5 6 7 8.

9 10 11 12 represent outlet-orifices in the 40 tube 2, one of which connects said tube with each of the compartments.

13 represents a valve-stem provided with a centrally-fixed ball-valve 14 and having a sliding movement in the oppositely-disposed 45 orifices 9 and 11, and 15 represents a similar valve-stem, also provided with a centrally-fixed ball-valve 16 and having a corresponding movement in the orifices 10 12.

17 represents the discharge-spout, comprising 50 a detachable sleeve which is threaded at its lower end to engage a threaded collar 18 on the upper end of a valve-tube 37. An oil-

tube 20, provided with a beveled outer end 21 and a head 19 at its lower end, slides in said sleeve, and 23 represents a cylindrical 55 plunger secured to the head 19 of said oil-tube and provided with an internal valve-seat 24, which receives the disk valve 25, the stem 26 of which extends through the loose sleeve 27 and through an enlarged orifice 28 60 in the bottom head 29 of the valve-chamber 37, its projecting threaded end being provided with a bar-nut 30, which holds the valve in its seat and at the same time permits an unobstructed passage for the oil through the 65 orifice 28.

31 represents an elastic packing-ring on the plunger, and 32 a disk or follower against which the outer end of the spiral spring 33 rests, its inner end abutting against the head 70 29 to press the plunger outwardly against the valve 25.

The sleeve 27 is loosely mounted on the valve-stem 26, and its outer end is provided with beveled sides 34 35, which permit the 75 free passage of the oil through the orifice in the plunger, while its inner end is tapering in form to readily enter the orifice 28 in the head 29, and the diameter of the sleeve is such as to snugly fit said orifice 28 and cut off the supply of oil from the can. The operation of 80 the device is such that the oil in the can flows into the central tube 2 and fills the valve-chamber 37, and if the beveled end 21 of the oil-tube 20 be placed against a solid object or 85 point to be lubricated and pressure applied to the can the plunger will be forced backward in the chamber 37, so as to recede from the valve 25 and positively force the oil through the oil-tube 20 and discharge it at its 90 outer end, the sleeve 27 in the meantime closing the orifice 28 and preventing the exit of the oil in that direction. As soon as the pressure is released from the can the spring 33 restores the plunger to its normal position and 95 the chamber 37 is again filled with oil from the tube 2 and is ready for operation.

It will be observed that in whatever horizontal position the can be held the orifice in the bottom compartment will be closed by the ball-valve and the corresponding orifice in the uppermost compartment opened to permit the oil to flow by gravity into the tube 2.

Figs. 2 and 3 show, respectively, a monkey-

wrench and a socket-wrench embodying my improved oiling device. In these figures 1^a represents the hollow handle of the wrench, which forms the oil-reservoir. 17 is the sleeve threaded onto the handle and provided with the discharge-tube 20. 31, 32 represent the elastic packing-ring and disk or follower; 27, the sleeve; 24, the valve having the stem, and 33 the spiral spring for normally holding the valve closed. The operation of the oiling attachment in these constructions is essentially the same as in Fig. 1, the only difference in construction being that the sleeve 17 forms the valve-chamber. The socket-wrench shown in Fig. 3 is provided on one of the inner sides of its socket-head 38 with a plate-spring 39, which serves to clamp the nut in the socket after it has been detached from the axle.

Although I have specifically described the construction and relative arrangement of the several elements of my invention, I do not desire to be confined to the same, as such changes or modifications may be made as clearly fall within the scope of my invention without departing from the spirit thereof.

Having thus fully described my invention, what I claim as new and useful, and desire to secure by Letters Patent of the United States, is—

30 1. A detachable discharge-spout for oil-receptacles, comprising the cylindrical sleeve 17, the oil-tube 20, the plunger 23 connected therewith and provided with the valve-seat 24 and the valve 25, provided with the stem 26 provided with the bar-nut 30, the sleeve 27 loosely encompassing said stem and the spiral spring 33 encompassing said stem and sleeve and holding said plunger in contact with said valve, substantially as shown and 40 described.

2. A portable oiler, comprising the can 1 provided with the central concentric tube 2,

the lateral compartments and an independent orifice for each compartment communicating with the central tube 2, and a gravity-valve 45 adapted to simultaneously close one compartment and open the opposite compartment, in combination with a discharge-spout communicating with the tube 2, a plunger mounted in said spout, a valve mounted in said plunger, 50 and means substantially as described for operating said plunger to positively discharge the oil through said spout, as and for the purpose set forth.

3. In oiling devices, an oil-reservoir, a 55 valve-chamber attachably secured to one end thereof, a plunger-spout or discharge-tube sliding therein, a valve controlling the flow of oil therethrough, a stem attached to said valve and extending through said tube, a 60 sleeve connected with said stem, a spring acting on said sleeve and stem, and means for adjusting said valve-stem, substantially as described.

4. A portable oiler comprising a can 1 provided with the central concentric tube 2 and radial walls 4 forming lateral compartments, each of said walls being provided with a discharge-orifice, gravity-valves controlling said orifices, a cylindrical sleeve 17, an oil-tube 20 70 sliding therein, a plunger 23 connected with said oil-tube and provided with a valve-seat 24 and a valve 25 having a stem 26, a sleeve 27 loosely encompassing said stem, and a spiral spring 33 encompassing said stem and 75 sleeve 27 and adapted to hold said plunger in contact with said valve, substantially as described.

In testimony whereof I affix my signature in presence of two witnesses.

JOSIAH SCOTT SCARBOROUGH.
